US00D716667S

(12) **United States Design Patent**
James et al.

(10) **Patent No.:** **US D716,667 S**
(45) **Date of Patent:** **** Nov. 4, 2014**

(54) **FLEXIBLE POUCH**

(71) Applicants: **Timothy James**, Brooklyn, NY (US);
Haley A. Lowry, Houston, TX (US); **Jill**
M. Martin, Brazoria, TX (US)

(72) Inventors: **Timothy James**, Brooklyn, NY (US);
Haley A. Lowry, Houston, TX (US); **Jill**
M. Martin, Brazoria, TX (US)

(73) Assignee: **Dow Global Technologies LLC**,
Midland, MI (US)

(**) Term: **14 Years**

(21) Appl. No.: **29/446,105**

(22) Filed: **Feb. 20, 2013**

(51) LOC (10) Cl. **09-05**

(52) U.S. Cl.
USPC **D9/709**

(57) **CLAIM**

The ornamental design for a flexible pouch, as shown and described.

DESCRIPTION

FIG. 1 is a perspective view of a flexible pouch showing our new design;

FIG. 2 is a front elevation view thereof;

FIG. 3 is a left elevation view thereof;

FIG. 4 is a top plan view thereof;

FIG. 5 is a bottom plan view thereof;

FIG. 6 is a right elevation view thereof; and,

FIG. 7 is a rear elevation view thereof.

The broken lines in the drawings represent unclaimed environmental matter.

1 Claim, 4 Drawing Sheets
